(74) Attorney, Agent, or Firm — Cynthia R. Wright

(57) **CLAIM**

The ornamental design for a cooler, as shown and described.

DESCRIPTION

FIG. 1 is a top view of a cooler in a closed configuration showing my new design.

FIG. 2 is a front view thereof.

FIG. 3 is a bottom view thereof.

FIG. 4 is a top view of FIG. 1 in an open configuration.

FIG. 5 is a front view thereof.

FIG. 6 is a bottom view thereof.

FIG. 7 is a left side view of FIG. 2.

FIG. 8 is a right side view thereof.

FIG. 9 is a left side view of FIG. 5.

FIG. 10 is a right side view thereof.

FIG. 11 is a front, right, and top perspective view of FIG. 2; and,

FIG. 12 is a front, right, and top perspective view thereof shown in an open configuration.

The broken lines in the figures depict portions of the cooler that form no part of the claimed design.

1 Claim, 12 Drawing Sheets(56)
